UNITED STATES PATENT OFFICE.

JOHN A. SHARPS AND ISHMAEL G. CUTRIGHT, OF BUCKHANNON, WEST VIRGINIA,
ASSIGNORS TO THE CUTRIGHT SHARPS COMPANY, INC., OF BUCKHANNON, WEST
VIRGINIA.

SHADE-ROLLER FIXTURE.

1,389,603.

Specification of Letters Patent. Patented Sept. 6, 1921.

Application filed September 4, 1920. Serial No. 408,128.

To all whom it may concern:

Be it known that we, JOHN A. SHARPS and ISHMAEL G. CUTRIGHT, citizens of the United States, residing at Buckhannon, in the county 5 of Upshur and State of West Virginia, have invented certain new and useful Improvements in Shade-Roller Fixtures, of which the following is a specification.

The invention has for its object to provide means for preventing dust settling and accumulating on shade rollers and to provide supporting means for retaining the shade roller and protector in position so that either one or both may be readily removed, 15 placed in position or adjusted as required.

The drawings illustrate a preferred embodiment of the invention. However, we desire it to be understood that in adapting the same to meet different conditions, various changes in the form, proportion and minor details of construction may be resorted to without departing from the nature of the invention as claimed hereinafter.

Referring to the drawings hereto attached:—

Figure 1 is a front view of a shade roller and coöperating protector and mountings therefor, embodying the invention, parts being broken away to show more clearly the relationship of the elements.

Fig. 2 is a transverse section on the line 2—2 of Fig. 1, looking to the left as indicated by the arrow.

Fig. 3 is a cross section on the line 3—3 of Fig. 1, looking to the right as designated by the arrow.

Fig. 4 is a cross section of the protector or shield on the line 4—4 of Fig. 1, the shade roller being omitted.

Fig. 5 is a sectional detail on the line 5—5 of Fig. 2 showing an end portion of the protector and a portion of the mounting.

Fig. 6 is a front view showing the invention as applied to a spring actuated shade 45 roller and ordinary mountings.

Fig. 7 is a transverse section on the line 7—7 of Fig. 6, looking to the left as indicated by the arrow.

Fig. 8 is a cross section on the line 8—8 of Fig. 6, looking to the right as indicated by the arrow.

Fig. 9 is a sectional detail of the bracket and portion of the protector, on the line 9—9 of Fig. 7.

Fig. 10 is a detail perspective of a modified form of one of the fixtures which may be used upon the window frame, over which the lower end of the chain is adapted to pass.

Corresponding and like parts are referred to in the following description and indicated 60 in the several views of the drawings by like reference characters.

The shade roller 1 illustrated in Fig. 1 and the detailed views thereof is adapted to be operated by means of a sprocket chain 65 and for this purpose is illustrated in Fig. 1 as provided at one end with a sprocket wheel 2 for the reception of the sprocket chain, 2^a. The shade roller is of tubular construction and formed of sheet metal 70 which is bent into the form of a tube as indicated most clearly in Figs. 2 and 3. The longitudinal edge portions of the strip from which the shade roller is formed are separate to form a slot for the reception of the 75 end of the shade in a manner well understood. Two brackets of different formation are provided for the shade roller. The bracket receiving the sprocket wheel 2 comprises a base 3 and side pieces 4 and 5. This 80 bracket may be attached to the facing of a window or to the jambs and for this purpose the base 3 and the side piece 4 are provided with openings to receive fastenings. This is indicated most clearly in Figs. 1 and 85 2. Edge portions of the side piece 5 are cut away as indicated at 6 to admit of the fastenings being conveniently applied to the side piece 4 when the bracket is attached to the jambs of a window.

The bracket comprising the base 7 and supporting member 8 is adapted for universal application and may be applied to either end of the shade roller or to the facing or jamb of a window. As shown most clearly 95 in Figs. 1 and 3 the base 7 and the supporting member 8 are provided with openings to receive the fastenings by means of which the bracket is secured when adjusted in the required position. The outer end of the supporting member 8 is provided with an opening 9 of approximately T-form. One branch of the opening 9 extends through the outer end of the member 8 and is disposed to occupy a horizontal position when the 100 bracket is in service and supports a shade roller. The branches of the opening 9 are oppositely inclined as shown most clearly in 105

Fig. 3 so as to receive the journal of the shade roller and retain it in place against vertical displacement.

The brackets are provided with keepers 10 which are partly cut therefrom and pressed laterally. The bracket comprising the parallel side pieces 4 and 5 has the keeper 10 formed on the side piece 5 and projecting laterally from the outer side thereof. The bracket comprising the supporting member 8 is formed with two keepers 10 thereby adapting the same to be used either upon the right or the left hand side of a window. The protector or shield is adapted to occupy a position above the shade roller as indicated most clearly in Figs. 2 and 3. By having the protector disposed in the manner shown it prevents dust from settling upon the shade which is extremely objectionable. The protector is transversely curved and is supported at its ends by the brackets which form sustaining means for the shade roller. A curved bar 11 is secured to the inner side of each end of the protector and one end extends to form a shank which is adapted to engage a keeper 10. The shank is designated at 12 and is provided at one end with a shoulder 13 and at its opposite end with a lateral extension 14. The keeper 10 is comprised between the shoulder 13 and the lateral extension 14, hence the protector is positively held in the required position when applied to the brackets. The curved bar 11 is provided along its outer edge with inwardly extending ears 15 which are apertured to receive fastenings by means of which the curved bar is secured to the protector or shield. By having the bar 11 curved it is adapted to clear the journal and shade. The protector or shield preferably comprises two members or sections 16 and 17, which have sliding engagement whereby the protector is adapted to be lengthened or shortened as occasion may require according to the width of the window or the relative position of the supporting brackets. One of the sections has its longitudinal edge portions recurved to form guide ways which receive the longitudinal edge portions of the companion section. As shown most clearly in Figs. 2 and 4, the outer section 16 has its edge portions inwardly curved as indicated at 18 to receive the edge portions of the relatively inner section 17.

In the modification shown in Fig. 6 and the detailed views thereof, the shade roller 1^a is of the spring actuated type whereby the shade will automatically wind thereon in a

manner well understood. The shield or protector and the parts associated therewith are substantially the same as hereinbefore described in detail. The brackets 19 forming mountings for the shade roller and protector are of ordinary and well known construction with the possible exception that portions are partly cut from the brackets and pressed laterally to form the keepers 10 to receive the shanks of the bars 11 at the ends of the shield or protector.

As shown in Fig. 1 the chain 2^a passes over the roller 4^a carried by staple 8^a, the casing 3^a being tubular in shape and carrying a plunger 5^a. This plunger 5^a is engaged by means of a coil spring 6^a which is also mounted in the casing 3^a and holds the chain 2^a under tension. The plunger 5^a is provided with an eye 7^a, which eye may be secured in any suitable or desired manner to the casing or window frames, in this way permitting the chain 2^a to be held at a proper tension for efficient operation.

In Fig. 6 is shown a modified form of the fixture which is adapted to coöperate with the chain, and this fixture comprises a plate 20 having laterally bent flanges 21 arranged in parallel relation. The roller 22 is interposed between the flanges 21 and journaled thereon, this roller 22 being adapted to receive the chain 2^a. The plate 20 may be permanently fixed to the window frame by means of suitable securing means such as pins (not shown) passing through the apertures 23 formed in the plate 20.

Having thus fully described our invention what we claim as new and desire to secure by Letters Patent is:—

1. A dust shield for shade rollers provided at each of its ends with a reinforcing bar which has an end portion extending to form a supporting shank, the latter having a stop shoulder and a lateral extension at diagonally opposite points.

2. A dust shield for shade rollers provided at each of its ends with a reinforcing bar, the latter having inner lateral extensions secured to the shield and having an end portion extending to provide a supporting shank.

In testimony whereof we affix our signatures in presence of two witnesses.

JOHN A. SHARPS.
ISHMAEL G. CUTRIGHT.
